UNITED STATES PATENT OFFICE.

WILLIAM EDSON, OF SOMERVILLE, MASSACHUSETTS.

DISINFECTION-MAT.

SPECIFICATION forming part of Letters Patent No. 336,557, dated February 23, 1886.

Application filed January 31, 1885. Serial No. 154,567. (No model.)

To all whom it may concern:

Be it known that I, WILLIAM EDSON, of Somerville, in the county of Middlesex and State of Massachusetts, have invented a new and useful Improvement in Disinfecting-Mats, of which the following, taken in connection with the accompanying drawings, is a specification.

My invention has for its object so constructing a mat that it may contain a convenient receptacle for disinfecting substances, which may be readily removed from the mat when exhausted. I attain this object by the devices shown in the accompanying drawings, in which—

Figure 1 is a perspective view of one of my mats as it appears when complete. Fig. 2 is a perspective view of a device that I use for holding the disinfecting material; and Fig. 3 is a cross vertical section of my mat.

In making my mat I do not confine myself to any particular construction, as the invention may be embodied in a great variety of styles, shapes, and sizes.

In the drawings, A represents the mat proper, and B a lining. The two parts A and B are joined together on three sides, and left

open at one end, as indicated in Fig. 1. Thus a bag is formed which serves to hold the disinfecting material.

In Fig. 2 I have shown a quilt, c, the interior of which is filled with the disinfectant. The quilt c (shown at Fig. 2) is to be inserted into the bag formed by the mat A and its lining B. (See Figs. 1 and 2.)

Any of the well-known dry disinfectants may be used, either simple or compounded, and in case the chemical is deliquescent, or even liquid, it may be mixed with some absorbent—sawdust, for instance.

When desired, the quilt or receptacle c, Fig. 2, may be filled with a sachet of perfume-powder, or a compound of disinfecting and perfuming powders can be used.

What I claim is—

The combination of the mat A B with the receptacle or quilt c, said receptacle or quilt being filled with a disinfecting or perfuming substance.

WILLIAM EDSON.
